UNITED STATES PATENT OFFICE.

GUSTAV C. MAAG, OF NEW YORK, N. Y., ASSIGNOR TO CONTINENTAL GAS COMPRESSING CORPORATION, A CORPORATION OF NEW YORK.

APPARATUS FOR OBTAINING LIQUID HYDROCARBONS.

1,142,525.

Specification of Letters Patent.

Patented June 8, 1915.

Application filed June 11, 1914. Serial No. 844,427.

To all whom it may concern:

Be it known that I, GUSTAV C. MAAG, a citizen of Germany, and a resident of New York city, New York, have invented certain 5 new and useful Improvements in Apparatus for Obtaining Liquid Hydrocarbons, of which the following is a specification.

This invention relates generally to apparatus adapted to be employed in the recovery 10 in isolated liquid form of hydrocarbons of the methane series and it is particularly adapted to the production of gasolene from casing head gases, or gases having a similar constitution.

15 Several attempts have been made heretofore to obtain gasolene from casing head gases by first subjecting the gases to a very high degree of compression and then subjecting the compressed gases to cooling from 20 an outside source. The main difficulty with these methods was to be found in the lack of economy in the process and in the lack of stability in the product. The pressure was kept very high in order that no part 25 of the gasolene should escape condensation, but as a result of such compression a great many ingredients of the casing head gases were condensed with the gasolene and subsequently evaporated out of it again when 30 the gasolene was exposed to the atmosphere.

The heat of compression also played an important rôle in rendering such processes uneconomical. So far as the product was concerned, it was likely to differ in constitution 35 from day to day according to local temperature and atmospheric conditions. The local temperature, combined with the frequent dearth of water in the gas regions, tended to make the external cooling process a variable, 40 unreliable and expensive factor. In order to render the products marketable, the compressed liquids were frequently exposed for a length of time in weathering tanks in which the more volatile compressed constituents 45 were allowed to pass off again into the air and this manifestly rendered nugatory the labor of compressing and liquefying such volatile ingredients as became dissipated in the weathering tanks. I have invented 50 an apparatus which will overcome these defects and which is designed to produce a substantially uniform quality of commercial gasolene continuously and independent of local (temperature) conditions, requiring no 55 weathering tanks or special treatment of the

gasolene. The process which I employ in this apparatus is the process described in the patent issued to Emil Schill on June 16, 1914, and the apparatus devised by me is one apparatus in which that process can 60 be carried out. I have also made use of the underlying features of the apparatus for which Letters Patent have been applied for by Emil Schill on June 1st, 1914. I have, however, in devising my improved apparatus, adapted it more particularly to producing gasolene, whereas the inventions of Emil Schill are designed with special reference to the production of pentane, gasolene being treated as a by-product. 70

In this specification I shall adopt the same terminology employed in the Schill application and refer to the mixed gases as composed generally speaking of the methanes, the pentanes and gasolene. 75

My invention is shown in the accompanying drawings, in which—

Figure 1 represents a top view of the plant and Fig. 2 a detail view of a modified form of oil separator connections. 80

In the drawing A represents the compressor and B the belt that drives it.

C C' are the steam cylinders which communicate with the compression cylinders D D'. 85

E represents the pipe communicating with the source of supply such, for example, as the head of an oil well, or of a storage tank or pipe line. The mixed gases which compose this supply enter the tank F through the pipe E. The tank F is a cleaning tank and the gases entering it at the top deposit therein rust, oils, water, etc., such as are readily separated by gravity. The gases thus comparatively purified pass from the tank F through pipe G to the meter M, the function of which is to measure the quantity of gases which are subsequently compressed in the cylinders D D'. The gases first enter the low pressure cylinder D and are met 90 therein by a heat absorbing agent, such as glycerin, in the condition of very fine minute subdivision, which enters the cylinder through an atomizing nozzle supplied through the pipe line L. The heat absorbing agent must enter the cylinder in a very finely atomized form, such as spray or mist. Glycerin may be used as the heat absorbing medium but I may employ a number of other equivalent agents. 100

110

After the gases have been compressed in the low pressure cylinder D, they are conveyed by means of the connection shown in the dotted lines to the high pressure cylinder D', this connection being indicated as located below the apparatus shown. The cylinder D' is termed a high pressure cylinder as compared with the cylinder D, although the pressure employed in my apparatus in the cylinder D' is materially less than the pressure which has been employed in connection with processes for compression of natural gases. A pressure of 200 pounds in this cylinder is sufficient to bring about commercial results and even lower pressures may be used, care being taken that the pressure and temperature do not produce conditions such that the hydrocarbon gases change from their gaseous form. The heat absorbing agent removes from those gases the water contained in them in the form of an aqueous vapor and also the water-soluble impurities such as NH_3 , H_2S and others, as well as heavier products. The heat generated by compression is not transferred to the gases, by reason apparently of the intermolecular lubrication which seems to take place; to some extent the heat of compression is also absorbed by the glycerin. In the high pressure cylinder D', the gases are subjected to such a degree of pressure as is required to reduce them to the proper condition for further treatment in the remainder of the apparatus and there is also given to them the necessary power to pass through the remaining portions of the apparatus. From the high compression cylinder D' the compressed gases are brought into the top of the separator H in which the glycerin is recovered. The pipe I connects the bottom of the separator H with the top of the glycerin tank J. The pressure in the separator H is sufficient to raise the liquid in the pipe I. From the bottom of the storage tank J the glycerin is carried through the pipes K-L to the spraying nozzles through which it is injected into each of the compression cylinders in a very finely divided condition. The pipe L during a portion of its length is shown as externally cooled by the double pipe water cooler N. The by-pass O is used when the storage tank J is cut out of the system for purposes of cleaning, refilling, replacing or repair. From the upper part of the separator H the compressed gases pass into the coil condenser P, which I call the gasoline condenser and which may be cooled by the expanded permanent gases in the manner which will be described later. The temperature in the gasoline condenser P is regulated according to the hydrocarbons contained in the gas, *i. e.* their partial pressures, and should be approximately 40° to 70° C. , and so as to be substantially constant with respect to the compressed gases so as

to produce a uniform quality of gasoline which, as it collects, runs off from the bottom of the condenser P into the tank Q from which the gasoline may be withdrawn as desired through the pipe 201. 70

The uncondensed compressed gases which now consist of methane and pentane as a separated gas leave the top of the collecting tank Q through the pipe 202 and enter the top of the pentane condenser 203. The liquid 75 which is condensed in this coil condenser 203 consists substantially of pentane and is withdrawn at the bottom through the pipe 204 into the pentane collecting tank 205 from which the pentane can be withdrawn 80 at the pipe 209. The valves 206, 207, 208, 221 and 222 are provided to enable the condenser 203 to be cut out of the system in case of accident, the necessity for repairs or the like without interrupting the remaining 85 parts of the operation. After the gas passes through the pentane condenser 203, it has been deprived of all liquefiable constituents and is in the form of dry compressed methane. This dry gas which first travels 90 from the pentane condenser 203 through the pipe 204 into the pentane collector 205, passes out of the latter through the pipe R from which it passes into the compound steam cylinders C C' where such pressure as 95 it may be under will be converted into energy. The gases as they leave the compound cylinders C C' expand into the separator S where such oils or lubricants as they may have gathered will be removed from them. 100 The expansion of these gases at this point, following the conversion of their pressure into energy, develops a very material reduction of temperature. The cold gases leave the separator S through the pipe S' and into the pipe 210. The relief valve T may be used in starting the apparatus so that the gas engine shall not work against the load. The valve T is closed as soon as pressure is 105 properly developed. The cold gases in the pipe 210 first pass into the bottom of the pentane condenser 203 leaving the top of that condenser and passing through the cross-T 211 into the gasoline condenser P. The condensation of the pentane increases 110 the temperature of the cold methane and thus aids in the regulation of the temperature desired in the gasoline condenser P. By a suitable regulation of the valve, the temperature in the pentane condenser 203 115 can be so controlled that the methane emerging from that condenser will have the proper temperature for condensing the gasoline out of the richer compressed mixed gases in the gasoline condenser P. The methane finally 120 passes out of the gasoline condenser P through the pipe 212 and into pipe 213 and out of the system to a gas meter, or directly 125 to a consumption plant.

For the purpose of more minutely regu- 130

lating the temperature in the condenser P, the valve 214 may be employed to bring the desired quantity of cold gases directly into the condenser P or the valve 215 may be opened to permit cooling gases from the pentane separator 203 to pass directly out of the system and into pipe 213. The valves 216 and 217 are closed when it is desired to cut the pentane separator out of the system 10 altogether. The valves 218 and 219 serve partially to regulate the temperature in the gas condenser P, or to cut the cold gases out of that cylinder altogether. The valve 220 is opened when it is not desired to employ 15 the cold gases in connection with any of the condensers and in that case the valves 214, 217, 215 and 219 would be closed.

The separator S in practice may as shown 20 in Fig. 2 be placed between the expansion cylinders C—C'. There is a considerable drop in temperature of the gases as they leave the high pressure expansion cylinder which results in the condensation of vapors. The arrangement is such that these condensates shall not enter the low pressure expansion cylinder. Any condensates or lubricants either from the low expansion cylinder or which may be carried forward out of the separator S may be withdrawn from the 25 system through the pipe 223 arranged in connection with the pentane condenser 203.

Having thus described my invention, what I claim is:

1. The combination of a compressor for 35 compressing natural gas mixtures containing gasolene, pentane and methane, an injecting nozzle communicating with the interior of said compressor adapted for the injection of a finely divided liquid, a collector 40 to receive liquid constituents of the compressed gases as they leave the compressor, a condenser within which the gasolene is liquefied, a second condenser within which the pentane is liquefied while in the form of a

separated gas, means for conducting the 45 compressed gases from the collector through the gasolene condenser, a connection for withdrawing uncondensed gases from the gasolene condenser into the pentane condenser, means for causing the gases uncondensed in the pentane condenser to expand and a conduit containing the cold expanded gases leading first into the vicinity of the pentane in the pentane condenser and subsequently into the vicinity of the gasolene in 55 the gasolene condenser.

2. The combination of a compressor for compressing natural gas mixtures containing gasolene, pentane and methane, an injecting nozzle communicating with the interior of said compressor adapted for the injection of a finely divided liquid, a collector to receive liquid constituents of the compressed gases as they leave the compressor, a condenser within which the gasolene is liquefied, a second condenser within which the pentane is liquefied while in the form of a separated gas, means for conducting the compressed gases from the collector through the gasolene condenser, a connection for 60 withdrawing uncondensed gases from the gasolene condenser into the pentane condenser, means for causing the gases uncondensed in the pentane condenser to expand and a conduit containing the cold expanded 65 gases leading first into the vicinity of the pentane in the pentane condenser and subsequently into the vicinity of the gasolene in 70 the gasolene condenser and regulating means for controlling the temperature of the cold 75 expanded gases in the said two condensers.

In testimony whereof I have hereunto set my hand in the presence of two subscribing witnesses.

GUSTAV C. MAAG.
